UNITED STATES PATENT OFFICE.

ROBERT HOFSTETTER, OF CHICAGO, ILLINOIS, ASSIGNOR, BY DIRECT AND MESNE ASSIGNMENTS, OF THREE-EIGHTHS TO F. C. MANNING, OF NEWARK, NEW JERSEY, ONE-FOURTH TO ALBERT ERICKSON, AND THREE-EIGHTHS TO CHARLES KRATSCH, BOTH OF CHICAGO, ILLINOIS.

FUEL-INJECTION DEVICE FOR OIL ENGINES.

Application filed May 5, 1920. Serial No. 379,193.

To all whom it may concern:

Be it known that I, ROBERT HOFSTETTER, a citizen of the United States, residing at Chicago, in the county of Cook and State 5 of Illinois, have invented new and useful Improvements in Fuel-Injection Devices for Oil Engines, of which the following is a specification.

This invention relates to means for the 10 delivery and atomization of heavy oils to the combustion chamber of oil burning engines and consists essentially of a mechanical atomizer and a primary cylinder both attached to the inlet valve and forming a 15 part thereof.

In order to better understand this invention it is necessary to consider the fact that all oils used as engine fuels contain a certain amount of light hydro-carbons, 20 which once separated from the fuel as a whole can readily be ignited. If this ignition can be forced to take place in a receptacle which also contains the residue of the oil from which the hydro-carbons have 25 been separated, it is readily to be seen that the heat of the explosion of the light hydro-carbons will not only vaporize but also ignite the residue of the oil, thus giving complete combustion of all the fuel de- 30 livered to the receptacle.

This process of separate primary ignition and complete combustion is obtained by means illustrated in the accompanying drawing in which—

35 Figure 1 is a cross section through the upper portion of an engine cylinder showing the invention incorporated thereto.

Figure 2 is an enlarged sectional view of the intake valve, the stationary bracket, 40 and the bracket extension.

Similar letters refer to similar parts throughout the two views.

The cylinder A, contains the piston B, and is closed on top by the cylinder cover 45 C, this cover is equipped with inlet valve F, exhaust valve G, which two valves are operated by valve rocker arms D, and L, these in turn being actuated by push rods I, and K, which receive their motion from 50 a 2 to 1 camshaft (not shown). Valves F, and G, are kept closed by coil springs H, and W, when not actuated by the camshaft, push rods, and valve rocker arms.

In describing the operation of the engine it is assumed that the four stroke cycle engine is being employed and that the piston 55 is just starting down on the intake stroke. Valve F, is about to be opened by rocker arm D, which is forked and bears on disk T, locked by check nut U. In moving downward a vacuum is created in the hollow stem of valve F, and fuel drawn in through the hollow stationary extension Y, and bracket J, past check valve R, which is raised on each downward stroke and prevents the oil from returning to the supply 60 tank which is in connection with entrance V.

As the valve moves downward it unseats itself from the wall Q, of the cylinder 70 cover thereby permitting a charge of air to enter the cylinder 4. This charge of air in passing valve body 3, will be partly diverted through ports O, and enter the primary cylinder 1, and expelling through 75 holes P, therefrom any residue remaining of the burned charge of the previous cycle.

Having completed the downward stroke the valve will begin to move upward under the influence of coil spring H, and the following events will take place.

The oil inside the hollow valve stem is prevented from returning to the fuel tank as check valve R, closes. As the pressure due to coil spring H, increases the small 85 valve 2, mounted in the lower part of the valve body 3, is forced open as much as the distance between the adjusting screw M, and the bottom of the small valve 2, will permit. This distance is chosen so that the 90 fuel oil will enter the primary cylinder 1, in the form of a spray, thereby saturating the air in the primary cylinder with readily ignited oil vapor.

After valve F, is seated on walls Q, the 95 piston B, continues to travel upward thereby increasing the air pressure in the combustion chamber 4, and also in the primary cylinder 1, because the latter stands in communication with the combustion chamber 4, 100 through the openings P, which are drilled on a slight angle, thus compelling the air which now enters from the combustion chamber, to agitate the fuel oil which may have accumulated at the bottom of primary 105 cylinder 1, thereby vaporizing part thereof

and increasing the inflammability of the mixture in the primary cylinder 1.

As the air pressure increases the temperature rises finally to a point where the vapor contained in the primary cylinder 1, ignites which momentarily increases the pressure in the primary cylinder 1, and forces the still unvaporized part of the fuel oil out into the combustion chamber proper, in 10 which the air now has reached a temperature high enough to complete the combustion of all the fuel oil.

As this final combustion takes place, the temperature and the pressure increase and 15 this pressure is transmitted to the piston which by this time has passed its dead center point and is on the downward stroke. Having completed the downward stroke the exhaust valve G opens under the influence 20 of rocker arm L, and push rod I, and permits the burned charge to leave through the passage X.

After the piston B, reaches the uppermost position the exhaust valve X, closes and the 25 cycle described repeats itself.

The stop cock S, serves to regulate the amount of fuel to be fed into the primary cylinder and may be connected with a suitable centrifugal governor, thereby making 30 the regulation of the engine automatic.

I am aware that prior to my invention fuel injection devices for oil engines have been made with primary cylinders and I therefore claim only:

35 1. The combination, in oil engines, of a primary combustion chamber attached to the main air intake valve and forming part thereof, the seat of the intake valve being provided with holes, which form a communication between the primary combustion 40 chamber and the intake passage, when the valve is off its seat.

2. The combination in oil engines having a main air inlet valve, of a primary combus-

tion chamber attached to the main air inlet 45 valve and forming a part thereof, a hollow stem for said inlet valve open at the top through which fuel is supplied to said cylinder, a stationary bracket mounted on said engine, an extension carried by said bracket extending within said hollow valve stem and having an oil tight fit therein, a connection between said extension and a fuel tank, and a check valve within said connection.

3. A combination in an oil engine having 55 a main air inlet valve, of a primary combustion chamber attached to said inlet valve and forming part thereof, a hollow stem for said valve through which fuel is supplied to said cylinder, and an automatically operating check valve having a restricted lift within 60 said hollow stem.

4. A combination in an oil engine having 65 a main air inlet valve, of a primary combustion chamber attached to said inlet valve and forming part thereof, a hollow stem for said valve through which fuel is supplied to said primary combustion chamber, an automatically operating check valve having a restricted lift within 70 said hollow stem, and a means for adjusting the lift of said check valve.

5. In combination with a main air inlet 75 valve for internal combustion engines of a primary combustion chamber carried thereby in constant communication with the combustion space of the engine, means for supplying predetermined quantities of liquid fuel to said primary combustion chamber, and means for scavenging said primary cylinder when said inlet valve is open.

In testimony whereof I have hereunto set my hand in presence of two subscribing witnesses.
